(57) **CLAIM**

The ornamental design for a football training device, as shown and described.

DESCRIPTION

1. Football training device

FIG. 1.1 is a front perspective view of a football training device in accordance with my new design;

FIG. 1.2 is a rear perspective view thereof;

FIG. 1.3 is a right side view thereof, the left side view being a mirror image;

FIG. 1.4 is a front perspective view thereof, in a folded position;

FIG. 1.5 is a representative corner portion thereof; and

FIG. 1.6 is a portion of a side perspective view thereof.
